(57) **CLAIM**

The ornamental design for a case for wireless earphones, as shown and described.

DESCRIPTION

FIG. 1 is a perspective view of a case for wireless earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings are for the purpose of illustrating portions of the case for wireless earphones that form no part of the claimed design.
